[57] CLAIM

The ornamental design for a electric pump, as shown.

DESCRIPTION

FIG. 1 is a front-right-top perspective view of a electric pump, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view showing the application of my new design, with alternate nozzles connected; and,

FIG. 9 is another embodiment showing the application of my new design with multiple nozzles connected.
